UNITED STATES PATENT OFFICE.

HERBERT L. THOMPSON, OF ELGIN, ILLINOIS.

BEATER.

Application filed November 19, 1921. Serial No. 516,275.

To all whom it may concern:

Be it known that L. HERBERT L. THOMPSON, a citizen of the United States, residing at Elgin, in the county of Kane and State 5 of Illinois, have invented certain new and useful Improvements in Beaters, of which the following is a specification.

My invention relates to beaters or mixers of the type in which a beater arm is given 10 a rapid movement for mixing or whipping the contents of a jar or other container, and it has for one of its objects the provision of a new and improved construction and arrangement of parts by reason of which 15 the device may be easily and quickly assembled, the structure being simple and readily produced, whereby it may be manufactured from high grade material at a low cost. It is another object of my invention to provide 20 a new arrangement of parts by reason of which the device shall be adapted for convenient use, being preferably arranged for actuation by a water motor and to that end capable of being mounted on an ordinary 25 faucet so as to support in position the container for the materials to be beaten.

It is another object of my invention to improve devices of this type in sundry details hereinafter pointed out.

30 The preferred means by which I have accomplished my several objects are illustrated in the drawings, and are hereinafter specifically described. That which I believe to be new is set forth in the claims.

35 In the drawings—

Fig. 1 is a central vertical section through the preferred form of my improved device.

Fig. 2 is a perspective view of the preferred form of beating device employed, 40 comprising two beater arms formed integrally with each other.

Fig. 3 is a central vertical section through one form of means employed for connecting the motor housing with an ordinary faucet.

45 Fig. 4 is a top plan view of the threaded sleeve or collar by which the connection is effected between the faucet and the motor housing.

Fig. 5 is a top plan view, slightly broken 50 away, and partly in section.

Fig. 6 is a perspective view showing my improved motor mounted upon the upper end of a shaft with a modified form of beating device upon the lower end of the shaft.

55 Fig. 7 is a fragmentary view showing the

manner of mounting the modified form of device, as shown in Fig. 6.

Fig. 8 is a diagrammatic view for showing the action of the stream of water upon the vanes of the motor.

Fig. 9 is a view similar to Fig. 8, but illustrating the action under different conditions; and

Fig. 10 is a fragmentary view, similar to a portion of Fig. 5, but showing a modified form of construction.

Referring to the several figures of the drawings, in which corresponding parts are indicated by the same reference characters:

15 indicates a motor housing preferably formed of two sheets of metal correspondingly bent so as to be joined at their edges, as is best shown in Fig. 1. A cap 16 also

formed of sheet metal is secured by means of rivets 17 upon the lower face of the housing 15, both the cap 16 and the lower face of the housing 15 being offset, for holding firmly in position a bearing block 18.

A shaft 19 extends upwardly through the bearing 18, said shaft having fixedly mounted 55 upon its upper end a motor 20 of the type hereinafter described. Upon the lower end of the shaft 19 I have provided a beating device 21 which is adapted to be rotated by

the motor 20 within a jar 22 which is detachably held in position within the cap 16 by means of screw threads. In use, with

the jar 22 held rigidly in position with respect to the housing 15, with the beating device 21 extending down into the materials 60 to be mixed or beaten within the jar 22, and with the housing 15 preferably held in fixed

position with respect to a faucet or other stationary part, as hereinafter described, 65 water or other fluid under pressure is admitted to the housing 15, as hereinafter set forth, for causing a rapid rotation of the

motor 20 and the beating device 21.

Referring now particularly to Figs. 1 and 5, it will be seen that the motor 20 comprises 70 a sheet of metal 23 which is cut and bent to provide a plurality of similarly arranged, outwardly extending vanes 24, the device

being preferably produced by a single stamping operation. The motor rigidly mounted upon the upper end of the shaft 19 by riveting, washers 25 being preferably

provided above and below the sheet 23 for reinforcing the structure. As is clearly 80 shown in Fig. 1, the lower washer 25 rests

directly upon the bearing block 18 for supporting the motor and the shaft 19.

As is best shown in Fig. 2, the beating device is in the form of a loop, comprising a cross bar 26, formed of a strip of metal, having beater arms 27 formed integrally therewith, such beater arms 27 converging towards their upper ends. At its middle point, the cross bar 26 is provided with an oblong opening 28 which is adapted to fit snugly about a flattened portion 29 at the lower end of the shaft 19, whereby the cross bar 26 and the beater arms 27 are caused to revolve with the shaft 19 about its vertical axis. At the point 30, the shaft 19 is provided with a circumferential groove which engages with openings 31 through the inwardly turned upper ends of the arms 27, the engagement of the openings 31 with the shaft 19 at the groove 30 serving to hold the arms 27 inwardly towards each other beyond the normal position of the arms as shown in Fig. 2, the resilience of the device being sufficient for holding the device securely in position. By the provision of this construction, the assembling of the beating device upon the shaft 19 after the insertion of the shaft through the bearing block 18 is very quickly and readily effected without the use of any retaining means other than the shaft and the beating device. As is clearly shown in Fig. 1, a spacing sleeve 32 is provided between the upper end of the beater arms 27 and the lower end of the bearing block 18. A support is also provided for the circular lower end portion 33 of the shaft, such support being in the form of a loop or yoke 34 formed of a strip of metal, the upper ends of the arms being secured in position within the cap 16 by means of the rivets 17, whereby the yoke is secured in position at a minimum expense. As is best shown in Fig. 1, the cross bar 26 is bent slightly at its middle point so as to provide a limited bearing for the beating device 21 upon the yoke 34.

Coming now to the means for removably attaching the housing 15 to a faucet or other source of fluid under pressure, 35 indicates a thimble fixedly secured in the upper face of the housing 15 and opening upwardly therein. Revolubly mounted about the thimble 35 above the housing 15 is a screw-threaded sleeve or collar 36 which is adapted to cooperate with a correspondingly screw-threaded part to which attachment is to be made. A gasket 37 of any approved type is mounted within the sleeve 36 upon the upper face of the thimble 35. As will be readily understood, by bringing the thimble 35 into registry with the end of the faucet or other pipe, upon the compression of the gasket 37 between the upper end of the thimble and the end of the faucet by a tightening of the threaded sleeve 36, a rigid

and tight connection is effected between such faucet or other pipe and the thimble 35. In the construction shown in Fig. 3, the screw-threaded sleeve 36 cooperates with a correspondingly screw-threaded sleeve 38 held by means of set screws 39 upon the lower end of a faucet 40. By this construction, the housing 15 and the jar 22 are held securely in stationary position with respect to the faucet 40 so as to insure operation of the motor to the best advantage.

As is clearly shown in Fig. 1, the thimble 35 is provided with a horizontally disposed opening 41 at one side thereof, so as to direct a stream of water or other fluid under pressure into contact with the vanes 24 at one side of the axis of the shaft 19, so as to procure the desired operation of the motor 20. As is also shown in Fig. 1, the housing 15 is provided with an air vent 42 in its upper face directly above the shaft 19, such air vent being adapted to prevent the formation of a partial vacuum within the housing 15 as the water or other fluid under pressure escapes from the housing through the drain pipe 43.

In Figs. 6 and 7, which show a slight modification, the motor is mounted upon the upper end of a shaft 44 which is provided upon its lower end with a beating device 45 in the form of a plate having downwardly inclined wings 46. For this form of beating device, it has been deemed unnecessary to provide a support for the lower end of the motor shaft, but an extended bearing for the upper end of the shaft is provided by the provision of a sleeve 47 connected with the bearing block 18 in lieu of the sleeve 32 of the construction shown in Fig. 1. For holding the shaft 44 against withdrawal from the sleeve 47 and bearing block 18, I have provided a collar 48 tightly fitted upon the shaft 44 below the lower end of the sleeve 47.

In Fig. 10 I have illustrated another modification, the thimble 35 of that construction being provided with a plurality of parallel openings 49 therethrough for the delivery of a plurality of parallel streams of water or other fluid under pressure upon the motor 20, in lieu of the single stream provided through the opening 41 of the construction first described.

In Figs. 8 and 9 I have illustrated diagrammatically the manner in which the stream of water or other fluid under pressure is deflected effectively from one vane to another in the operation of the wheel under different conditions. In Fig. 9, which illustrates a light load condition, I have illustrated three phases of operation, (1) with the head of a portion of the stream from the opening 41 coming into contact at 50 with the outer edge of the vane 24, shown in dotted lines and marked a^1 ; (2) with the head

of the same portion of the stream having advanced inwardly along the face of the said moving vane to the point 51 at its inner edge, the vane in its changed position being indicated by a^2 ; (3) with the head of the said portion of the stream coming into contact at 52 with the vane b next ahead of the vane a at the then-assumed position of the said vane which is marked b^3 . Under such conditions the stream is seen to strike first one vane, and later the vane next ahead, operating effectively upon both of said vanes. While I have illustrated the action of the head of the stream only, it will be understood that under varying conditions, as the motor rotates, the stream is deflected from one to another of the vanes for operation upon such vanes successively.

In Fig. 8, which illustrates a heavier load condition, I have indicated also three phases of operation,—(1) with the head of a portion of the stream from the opening 41 coming into contact at 53 with the outer edge of the vane 24, shown in dotted lines and marked a^1 ; (2) with the head of the same portion of the stream having advanced inwardly along the face of the said moving vane to the point 54 at its inner edge, the vane in its changed position being indicated by a^2 ; (3) with the head of the said portion of the stream coming into contact with the vane c , which is the second vane ahead of the vane a , such contact being at the point 55 at the then-assumed position of the said vane c , which is marked c^3 .

In the operation of my improved wheel, the water or other fluid delivered under pressure is permitted to escape readily, the volume of such fluid being substantially very small compared with that of the housing and with that of the pipe 43. It will be understood that the escape of the actuating fluid is assisted by the provision of the air vent 42 by which any tendency to formation of a partial vacuum is prevented. This air vent 42 is particularly effective for preventing the tendency to form a vacuum in view of the arrangement of the parts, comprising the upwardly directed vanes which have complete clearance between them at their upper edges, whereby the formation of partially closed pockets is prevented.

This application is being filed as a continuation in part of my application Serial No. 496,090, filed August 27, 1921. No claim is made herein upon the form of the power wheel per se, such subject matter being covered by my said copending application.

60 I claim:

1. In a beater, the combination of a water wheel casing relatively thin vertically in proportion to its lateral dimensions, a thimble secured to and extending into the top of said casing at one end thereof and provided

with means for connection with the downturned end of a faucet to support the casing in a horizontal position and projecting from the faucet at one side thereof, a water wheel revolvable in said casing on an axis substantially vertical and provided with a beater shaft extending through the bottom of the casing, a beating device on said shaft, said thimble being closed at the bottom and formed with a jet orifice in the side positioned to direct a stream of water against said water wheel, a vessel into which the beating device projects, and means on the under side of the casing for removably supporting said vessel.

2. A beater comprising a motor housing, a bearing in the lower face of said housing, a shaft extending into said housing through said bearing, and a beater arm mounted on said shaft and held in position thereon by yielding engagement with a circumferential groove in said shaft.

3. A beater comprising a motor housing, a bearing in the lower face of said housing, a shaft extending into said housing through said bearing, and a beater device comprising a strip of metal bent to form a cross bar secured on said shaft and held against rotation with respect thereto, and two upwardly converging arms having a yielding engagement with a circumferential groove in said shaft adapted normally to prevent withdrawal of the beater device from the shaft.

4. A beater comprising a motor housing having a bottom wall of sheet metal, a bearing block fixed in an offset pressed in the bottom wall of the housing, a shaft extending into said housing through said bearing, a beater device mounted on the lower end portion of said shaft, and a cap secured on the under face of said housing upon said bearing block serving to brace the bearing and to removably support a jar from said housing.

5. A beater comprising a motor housing having a bottom wall of sheet metal, a bearing block fixed in an offset pressed in the bottom wall of the housing, a shaft extending into said housing through said bearing, a beater device mounted on the lower end portion of said shaft, and a cap secured on the under face of said housing about said bearing block and being also offset slightly for reinforcing the bearing block with respect to the cap and housing.

6. In a beater, the combination of a water wheel casing relatively thin vertically in proportion to its lateral dimensions, a thimble secured to and extending into the top of said casing at one end thereof and provided

a water wheel revoluble in said casing on an axis substantially vertical and provided with a beater shaft extending through the bottom of the casing, a beating device on 5 said shaft, said thimble being closed at the bottom and formed with a jet orifice in the side positioned to direct a stream of water against said water wheel, a vessel into which the beating device projects, means on the 10 under side of the casing for removably supporting said vessel, and a water discharge pipe extending downwardly from the bottom of the casing at one side of said vessel.

7. A beater as set forth in claim 6, in 15 which the housing is larger at one end than at the other, with the water wheel located in the larger end and the thimble and water discharge pipe located at the smaller end portion.

20 8. In a beater, the combination of a vessel, means for supporting the vessel from the top, a beater shaft, a yoke the ends of which are attached to the under face of said supporting means and the middle of which 25 is perforated to provide a bearing for the shaft, and a beating device in the form of a loop the middle portion of which is perforated and loosely and non-rotatably interlocked with the lower end of the shaft, 30 and the ends of which are provided with perforations through which the upper portion of the shaft extends.

9. In a beater, the combination with a 35 water wheel casing relatively thin vertically in proportion to its lateral dimensions, a thimble secured to and extending into the top of said casing at one end thereof provided with means for connection with the downturned end of a faucet to support the 40 casing in a horizontal position and projecting from the faucet at one side thereof, said thimble being closed at the bottom and formed with a lateral jet orifice, a vessel, means on the under side of said casing for 45 removably supporting said vessel, a beating device in said vessel provided with a shaft extending into said casing, and a water wheel fixed to said shaft comprising a disc formed with vanes arranged so that 50 as the wheel rotates the jet from the orifice in the thimble is deflected from each of the vanes against which it first impinges to and against another vane in the direction to give an additional forward impulse to the 55 wheel.

10. In a beater, the combination of a casing 60 relatively thin vertically in proportion to its lateral dimensions, means for connecting said casing with the down turned end of a faucet and directing water from the faucet into the casing in a substantially horizontal jet of small size relative to the cross sectional area of the faucet, a vessel, means on the under side of the casing for 65 supporting said vessel, a beater in the vessel

having a shaft extending into said casing, and a water wheel comprising a horizontal disc fixed on said shaft and provided with a plurality of vanes projecting from one face thereof into the path of said jet. 70

11. In a beater, the combination of a casing relatively thin vertically in proportion to its lateral dimensions, means for connecting said casing with the down turned end of a faucet and directing water from the 75 faucet into the casing in a substantially horizontal jet of small size relative to the cross sectional area of the faucet, a vessel, means on the under side of the casing for supporting said vessel, a beater in the vessel 80 having a shaft extending into said casing, and a water wheel comprising a horizontal disc fixed on said shaft and provided with a plurality of vanes projecting from one face thereof into the path of said jet and arranged so that the jet is deflected from each of the vanes against which it first impinges to and against another vane in a 85 direction to give an additional forward impulse to the wheel.

12. In a beater, the combination of a casing relatively thin vertically in proportion to its lateral dimensions, means for connecting said casing with the downturned end of a faucet and directing water from the faucet into the casing in a substantially horizontal jet of small size relative to the cross sectional area of the faucet, a vessel, means on the under side of the casing for 90 supporting said vessel, a beater in the vessel having a shaft extending into said casing, and a water wheel comprising a horizontal disc fixed on said shaft and provided with a plurality of transversely curved vanes 95 projecting from one face thereof into the path of said jet and arranged so that the jet is deflected from each of the vanes against which it first impinges to and against another vane in a direction to give an additional forward impulse to the wheel. 100

13. In a beater, the combination of a horizontally extended, vertically shallow casing, a vessel, means for supporting the vessel below the casing, means for connecting the casing to the downturned end of a faucet and for directing the water from the faucet into said casing in a small, substantially horizontal jet, a beater in said vessel having a shaft extending into said vessel, and a water wheel on the end of said shaft comprising a disc provided with a plurality of vanes arranged obliquely with respect to radial lines of the disc, transversely curved and disposed so that said jet impinges on the concave sides thereof. 110

14. In a beater, the combination of a horizontally extended, vertically shallow casing, a vessel, means for supporting the vessel below the casing, means for connecting the casing to the downturned end of a faucet 115 120

and for directing the water from the faucet into said casing in a small, substantially horizontal jet, a beater in said vessel having a shaft extending into said vessel, and a water wheel on the end of said shaft comprising a disc provided with a plurality of vanes arranged obliquely with respect to radial lines of the disc, transversely curved

and disposed so that said jet impinges on the concave sides thereof, said casing having an arcuate portion for the water wheel and a narrowed portion provided with a water outlet and with the means aforesaid for connecting the device to the faucet.

HERBERT L. THOMPSON.
